FLEXIBLE BRACELET

Michel Barmache and George E. Lederman,
New York, N. Y.

Application October 25, 1945, Serial No. 624,548

8 Claims. (Cl. 59—80)

1.

Our invention relates to bracelets or the like, and, more particularly to bracelets comprising a series of interlocking links or members.

Objects of our invention are a bracelet where the angular positions of adjacent members are variable whereby the entire bracelet appears to be flexible, a bracelet which can form a more or less circular or oval ring or a ring of uniform or variable curvature, and a bracelet which conforms to the shape or to the curvature of the wearer's arm or wrist.

In the following, we designate the direction of the wearer's arm or the direction of the axis of the ring formed by the assembled bracelet by "the axial direction," and any plane positioned perpendicular to this axial direction by "a ring plane." Other objects are to restrict the flexibility of the bracelet to the ring planes, to prevent the links from relative shift in axial direction, to provide the links with means guiding one link relatively to the subsequent or adjacent link in a ring plane and in a curved way, to conceal these guiding means within the links, and to protect the same from dust, mechanical injury and any other damage.

Further objects are a bracelet which can be worn without any inconvenience, a bracelet of pleasant appearance, a bracelet comprising alternately arranged larger and smaller members, a bracelet having links accurately arranged in one plane, and a bracelet which contacts the wearer's skin at intervals and, thereby, does not obstruct skin breathing and perspiration, but which, nevertheless, has a solid appearance.

Still other objects are to obtain these results with simple and reliable means, and to provide a method whereby such a bracelet can be easily, quickly and reliably made and assembled.

Still further objects and advantages will appear from the following description of an exemplifying embodiment of our invention, from the appended claims and from the accompanying drawing in which:

Fig. 1 shows a view of two different members in a condition where these members are not yet assembled.

Fig. 2 shows a view of the same members, seen from the left side in Fig 1.

Fig. 3 shows a partially sectional view of a few members in assembled condition, the members being seen in the same axial direction as in Fig. 2.

Fig. 4 shows a view of the entire bracelet, seen in axial direction.

2.

Figs. 1, 2 and 3 are represented on an enlarged scale.

Referring to the drawing, numerals 1 indicate the larger, and 2 the smaller links or members, these two kinds of members being alternately arranged throughout the bracelet. The ends of this series of members may be closed or connected in any suitable manner. For example, the series of members have terminal members 12 similar to the members 2 and provided with slots, and a key 3 may be inserted in these slots whereby these terminal members are interlocked. Or, any other suitable lock may be affixed to the ends of the series of members.

Each member 1 has a housing 4 with a cavity 5 and two openings 6 which are positioned opposite to each other in that direction which is peripheral in the assembled ring. Preferably, 20 these openings are elongated rectangles of uniform size. One of these openings is bridged over by a strip or band 7 having ends affixed to the housing 4 near an outer and an inner edge of this opening. The strip 7 forms an arc projecting 25 into the interior of the cavity 5. A slot 8 is provided in the strip 7 and extends over a part of the distance between the strip's ends.

Preferably, each member 2 has the shape of a cylinder having a length fitting the distance 30 between two opposite edges of the openings 6 or equal to the longer sides of these openings, and having a diameter slightly larger than the distance between the two other edges of the openings 6 or than the shorter sides of these openings. The axis of this cylinder coincides preferably with the axis or center of the arc of the strip 7.

A projection 9 which may be a small cylindrical pin or stud extends preferably radially 40 from the surface of the member 2 and has a diameter fitting the slots 8. The pin 9 is so positioned that it passes through the adjacent slot 8 when the member 2 is placed into that opening 6 of a member 1 which is bridged by a strip 7. In this position the member 2 closes this opening, contacts the edges thereof, but is free to slide or turn relatively to these edges or the respective member 1.

After a member 1 and a member 2 are put 50 together in this manner, that part of the pin 9 which passes beyond the slot 8 into the interior of the member 1 is converted into a head 10 broader than the slot 8 whereby the strip 7 and the pin 9 interlock each other and the members 55 1 and 2, preventing withdrawal of the pin from

the slot, but permitting movement of the pin from one end of this slot to the other.

Preferably, the formation of the head 10 is performed within the cavity 5 by means of a tool which is introduced into this cavity through that opening 6 which is opposite to the opening contacted by the member 2. The two interlocked members can turn relatively to each other. The length of the slot 8 provides for such a turning movement within limits sufficient for flexible adaptation of the curvature of the bracelet.

After the first pair of members 1 and 2 have been connected in this manner, another member 2 is soldered or affixed in any other suitable manner to the housing 4 of the first member 1 in a position where this other member 2 is inserted in the other opening 6 of this housing. Then, the pin 9 of this other member 2 is introduced into a slot 8 of a second member 1 and secured to this second member in the same manner as described before. Then additional members 2 and 1 are alternatingly added in the same manner until all members of the bracelet are assembled.

The members 2 may be hollow. Preferably, the members 1 and 2 are made of gold or any other suitable metal.

We desire it understood that our invention is not confined to the particular embodiment shown and described, the same being merely illustrative, and that our invention may be carried out in other ways without departing from the spirit of our invention as it is obvious that the particular embodiment shown and described is only one of the many that may be employed to attain the objects of our invention.

Having described the nature of our invention, what we claim and desire to protect by Letters Patent is:

1. A bracelet or the like comprising a member having a cavity with an opening, a second member positioned adjacent to said opening, and interlocking means concealed in said cavity and comprising two movably connected parts, one of said parts being affixed to said first and the other to said second member.

2. A bracelet or the like comprising a member having a cavity with an opening, a second member contacting edges of said opening and rotatable relatively to said first member, and interlocking means concealed in said cavity and comprising two movably connected parts, one of said parts being affixed to said first and the other to said second member.

3. A bracelet or the like comprising a member having a cavity with a rectangular opening, a second member having a cylindrical shape of a length fitting the distance between two opposite edges of said opening and of a diameter larger than the distance between the two other opposite edges of said opening, said second member movably contacting the edges of said opening, and interlocking means concealed in said cavity and comprising two parts, one of said parts being

affixed to said first and the other to said second member, said parts guiding each other along an arc having the same axis as said second member.

4. A bracelet or the like comprising a member having a cavity with an opening, a second member positioned adjacent to said opening, a slotted strip affixed to said first member in an inwardly curved position bridging over said opening, and a pin affixed to said second member, passing through the slot of said strip and having a head broader than said slot.

5. A bracelet or the like comprising a plurality of members of two different kinds, each member of the first kind having a cavity with an opening, each member of the second kind having one side adjacent to said opening of one member of the first kind and having an opposite side affixed to another member of said first kind, and a plurality of interlocking means each concealed in one of said cavities and comprising two movably connected parts, one of these parts being affixed to the member containing said cavity and the other part to the adjacent member of said second kind.

6. A bracelet or the like comprising a plurality of members of two different types, each member of the first type having a cavity with two opposite openings, each member of the second type having two opposite sides adjacent to two of said openings belonging to different members of said first type, and being connected to said different members, at least one of these two connections being movable and comprising interlocking means concealed in one of said cavities.

7. A bracelet or the like comprising a plurality of members of two different kinds, each member of the first kind having a cavity with two opposite openings, each member of the second kind having two opposite sides contacting the edges of two of said openings belonging to different members of said first kind, one of said sides being affixed to the edges contacted by this side, the other side having a projection extending into the cavity situated beyond the edges contacted by the latter side, and a plurality of interlocking means, each positioned in one of said cavities and movably connecting the projection positioned in said cavity with the member containing said cavity.

8. A method for assembling a bracelet from a series of members, said method comprising introducing a projection of one of said members through an opening into a cavity of a second member, securing said projection to said second member within said cavity by means of a tool introduced through another opening into said cavity, closing said other opening with a third member, soldering said third member to said second member, introducing a projection of said third member into a cavity of a fourth member and so on until all members of the series are connected.
